GUARD FOR THE OPENING IN A WASTE RECEPACLE

Charles A. Hamilton, Glen Ellyn, Ill., assignor to CAH Industries, Inc., Franklin Park, Ill., a corporation of Illinois

Filed Dec. 27, 1965, Ser. No. 322

Term of patent 14 years

(Cl. D58—17)

FIG. 1 is a perspective view of a guard for the opening in a waste receptacle, embodying my new design;

FIG. 2 is a top plan view on an enlarged scale;

FIG. 3 is a side elevational view thereof; and

FIG. 4 is a sectional view taken on the line 4—4 of FIG. 2.

The broken line showing of a waste receptacle in FIG. 1 is for illustrative purpose only.

I claim:

The ornamental design for a guard for the opening in a waste receptacle, as shown and described.
